UNITED STATES PATENT OFFICE.

AUGUST C. RUTZEN, OF CLEVELAND, OHIO.

RECORD FOR PHONOGRAPHIC MACHINES.

1,276,968.

Specification of Letters Patent. Patented Aug. 27, 1918.

Application filed June 7, 1915. Serial No. 32,545.

To all whom it may concern:

Be it known that I, AUGUST C. RUTZEN, a citizen of the United States, residing at Cleveland, in the county of Cuyahoga and State of Ohio, have invented certain new and useful Improvements in Records for Phonographic Machines, of which the following is a specification.

This invention pertains to records for phonographic machines, and the invention consists in a strip of flexible material of the nature of a ribbon or piece of tape having sound reproducing channels or grooves formed therein and substituted for the cylinders or disks heretofore commonly used for this purpose.

In the accompanying drawings, Figure 1 is a plan view of a reproducing mechanism and a record embodying my invention, and Fig. 2 is a sectional elevation of said mechanism, lengthwise and showing a record mounted on a pair of rolls and a bearing roll between the same over or upon which the reproducing needle operates. Fig. 3 is a plan view corresponding substantially to Fig. 1 except that the reproducing mechanism is omitted and the middle portion of the record strip is broken out, bringing the two ends near together and showing the sound lines or channels enlarged.

The invention is comprised, first, in the sound recording strip 2. This strip is distinguished from all the prior art known to me by its flexibility and adaptability to be rolled or wound upon drums, rolls or spools 3 and to which the ends of the strip or film can be removably secured. For example, in Fig. 1, the said receiver is presumably on its way, line by line, across the surface of the record and will end with the last line on the finishing side of the strip. But if the operation be as shown in Figs. 2 and 3, with the strip wound initially on one roll 3 when the operation begins and adapted gradually to wind on the other roll as the reproduction proceeds, the shift from one sound line to the other may be made from line to line. Or if each line represents an entire piece the receiver may stop at the end of any one of said lines or be shifted to the next in a continuous movement in any way provided for the purpose.

The sound receiver or instrument 4 is fashioned substantially after the usual receiver with a diaphragm and the like, and a needle 7 thereon runs in the sound chan-

nels and transmits the sound to the receiver, as usual. The tubular pivoted arm 8 connects with the side of the receiver and serves both as a support therefor and as a sound transmitting medium to the horn usually connected with said tube but not shown herein.

The bearing roller 6 for the strip 2 between the two end rolls is adapted to support the said strip directly beneath the needle 7 and to coöperate therewith. A medium hard rubber sleeve 9 or the like covers the said roller and usually the roller rotates responsively to the travel of the strip 2.

The terminals or ends of strip 2 which fasten to spools 3 are shown in Fig. 3, and the linear sound record thereon as represented by the wavy lines 5 begins at the right at A and extends by a "switch back" into the second parallel line from the top at the left at B. Then this second line switches back at the right at C into the third line from the top, and the succeeding lines are similarly joined to produce a series of independent sound records arranged in parallel lines but so joined that only a reversal of travel of the strip is required at stated intervals to shift the sound reproducing needle from one to another successively. The junction of the parallel record grooves is preferably arranged as shown in Fig. 3, after the manner of a "switch back" railway, the inclined portions 10 of the groove serving to shift the sound box and stylus into line with the return groove, which will then be readily followed by the stylus, as its inclination is reversed. The strip may be of any given length so that each line may represent a complete record, or two or more successive lines may be used to comprise a complete record divided into sections representing separate verses or chapters of a musical or dramatic composition, etc. In this way a relatively narrow band or strip may embody innumerable selections, or a single composition of great length and duration, and by the use of motor driven mechanism adapted to automatically reverse the movement of the strip when the needle is switched from one line to the next, it is possible to give a continuous performance for an indefinite period of time which is only limited by the width and length of the strip and the number of lines thereon. A machine for utilizing a strip record of the kind

set forth is shown and described in a co-pending application.

What I claim is:

A sound reproducing device comprising
5 two reels and a rotatable drum between the
same, in combination with a flexible strip en-
gaged on said reels and stretched over said
drum, said strip having linear sound repro-
ducing channels extending substantially

from end to end, and said channels having 10
terminals in switched back relations at their
ends with different channels for continu-
ous travel of the needle.

In testimony whereof I affix my signature
in presence of one witness.

AUGUST C. RUTZEN.
Witness:
H. T. Fisher.
